INVENTOR,
FRANK E. WOLCOTT
BY *Frank E. Wolcott*
ATTORNEY

UNITED STATES PATENT OFFICE

2,054,999

STRAINER

Frank E. Wolcott, West Hartford, Conn., assignor
to The Silex Company, a corporation of Connecticut

Application April 29, 1935, Serial No. 18,853

14 Claims. (Cl. 53—3)

My invention relates to strainers, and more particularly to resiliently connected strainers used on the upper bowls of vacuum type coffee makers.

5 It has for its object to provide an improved hook and pull connection for such a strainer whereby the same is connected to or released from the lower edge of the stem of an upper bowl. Further objects are to provide such a connection 10 which locates the line of pull on the pull member in alignment with the spring in such manner as to facilitate operation, and one which further provides a new and exceedingly sturdy yet simple construction not adapted to be twisted out of 15 place during use, and which also includes wholly new means for locating the hook relative to the lower end of the upper bowl stem. Other objects of my invention are to provide a construction which is adapted to be very cheaply manu- 20 factured and to be used in connection with standard strainers without appreciably increasing the cost thereof. These and other advantages of my improved construction will, however, hereinafter more fully appear.

25 In the accompanying drawing I have shown for purposes of illustration one embodiment which my invention may assume in practice.

In this drawing,—

Figure 1 is a side elevation, partially in section, 30 of an upper bowl and a strainer equipped with my improvement;

Fig. 2 is an enlarged detail view of the lower end of the strainer, showing my invention applied thereto;

35 Fig. 3 is a view similar to Fig. 2 but taken from the opposite side;

Fig. 4 is an end view of the lower portion of Fig. 3 as seen from the left, and

40 Fig. 5 is a detail sectional view on line 5—5 of Fig. 3.

In this illustrative construction, I have shown the upper bowl 1 of a vacuum type coffee maker having the usual stem 2 adapted to be inserted in and sealed in a lower bowl, not shown; this bowl 1 being provided with a usual strainer 3 having a depending spring 4 disposed within the stem 2 and this spring herein also being connected at its lower end to the lower edge 5 of the stem 2 and to a usual pull member or chain 6 by an improved connecting structure hereinafter described.

45 Referring more particularly to the lower end of the spring 4, it will be noted that the latter is provided with a usual elongated straight depending portion 7 and that this in turn is bent up to

form a generally usual U-shaped edge engaging portion 8. In my improved construction, however, it will be noted that, instead of providing a U-shaped portion 8 of doubled wire substantially throughout its length, as shown in my prior Patent No. 1,967,983, I herein bend a portion 9 downward and under the bottom of the U-shaped portion 8, and also provide another bend 10 upward and over the bottom of the U-shaped portion 8 substantially midway between the upstanding 10 sides of the latter. Moreover, this portion 10 is extended vertically downward as at 11, substantially below the U-shaped portion 8 and substantially parallel to the portion 4 but laterally off-set with respect thereto. As shown, the portion 11 15 is also provided with a lateral extension 12 on its lower end extending over toward and disposed directly beneath the portion 7. In the preferred construction, this pull 12 is also bent into the form of an eyelet 13 in alignment with the portion 7 and having a free end 14 bent into engagement with the bottom of the portion 12 and acting to enclose an intermediate portion 15 on the chain 6 below the top ball 16 on the latter.

50 As a result of this construction, it will be noted that the pull member or chain 6 acts directly in line with the portion 7 of the spring 4 so that operation is markedly facilitated. Further, with the portions 9, 10, 11, and 12 provided herein, a construction is provided wherein the portion 12 is 30 strongly supported on the portion 8 in such manner as not to be pulled out of the desired relation with respect thereto and the member 7. Moreover, it will be noted that the portion 10 provides 35 very convenient locating means for the portion 8 relative to the edge 5 of the stem 2 as shown in Figure 1, locating the parts definitely in the desired position illustrated therein. Moreover, it will be observed that due to its location midway between the arms of the U-shaped portion 8, this 40 member 10 will act to locate the member 8 definitely on the end of the stem 2 should the edge 5 inadvertently come on the opposite side of the member 10. Further, of course, the pull on the member 6 will remain in the desired alignment 45 with the portion 7 irrespective of the relative location of 8 and 5. It will also be evident that the construction is exceedingly strong and sturdy and adapted to be manufactured at small expense. These and other advantages of the same will, 50 however, be clearly apparent to those skilled in the art.

55 While I have in this application specifically described one form which my invention may assume in practice, it will be understood that this

form of the same is shown for purposes of illustration and that the construction may be modified and embodied in other forms without departing from its spirit or the scope of the appended 5 claims.

What I claim as new and desire to secure by Letters Patent is:

1. In a coffee maker strainer, an upper bowl having a stem, a strainer in said bowl having a 10 connection extending through said stem and including an elongated depending member having a hook connected to the lower end of the latter and engageable with the lower edge of said stem, and operating means for said hook rigidly connected thereto and disposed in substantial alignment 15 with said depending member.

2. In a coffee maker strainer, an upper bowl having a stem, a strainer in said bowl having a connection extending through said stem and including an elongated depending member having a hook connected to the lower end of the latter and engageable with the lower edge of said stem, and operating means for said hook comprising a laterally extending portion connected to and 20 spaced below said hook, and a pull member connected with said laterally extending portion at a point in line with said elongated depending member.

3. In a coffee maker strainer, an upper bowl 30 having a stem, a strainer in said bowl having a connection extending through said stem and having a hook connected to the lower end of the latter, and means in said hook for locating the latter relatively to the lower end of said stem.

35 4. In a coffee maker strainer, an upper bowl having a stem, a strainer in said bowl having a spring connection extending through said stem and having a hook connected to the lower end of the latter, and means in said hook for locating the latter relatively to said stem with the edge of said 40 stem disposed in operative positions on either side of said locating means.

5. In a coffee maker strainer, an upper bowl 45 having a stem, a strainer in said bowl having a spring connection extending through said stem and having a hook connected to the lower end of the latter, operating means on said hook, and locating means in said hook, said locating means comprising a portion dividing said hook into two 50 stem edge receiving portions and said operating means being disposed in alignment with the portion of said connection carrying said hook.

6. A strainer connection for coffee maker strainers having a depending portion carrying a 55 hook thereon, and a pull connection braced by

the hook and disposed in substantial alignment with said portion.

7. A strainer connection for coffee maker strainers having a depending portion carrying a hook thereon, and a pull connection overlying said 5 hook.

8. A strainer connection for coffee maker strainers having a depending portion carrying a hook thereon, and a pull connection disposed in alignment with said portion and having a portion 10 supported in said hook.

9. A strainer connection for coffee maker strainers having a portion carrying a hook thereon, and means dividing said hook into a plurality of stem edge engaging portions. 15

10. A strainer connection for coffee maker strainers having a portion carrying a hook thereon, and means dividing said hook into a plurality of stem edge engaging portions and having a depending laterally extended pull member connecting portion disposed in alignment with said 20 first mentioned portion.

11. A strainer connection for coffee maker strainers having a portion carrying a hook thereon, said portion and hook comprising a length of 25 wire and having an end portion extended downward from the outer end of said hook and upward and across the inside of said hook and then downwardly again.

12. A strainer connection for coffee maker 30 strainers having a portion carrying a hook thereon, said portion and hook comprising a length of wire and having an end portion extended downward from the outer end of said hook and upward and across the inside of said hook, said end portion 35 carrying a laterally extending eye portion.

13. A strainer connection for coffee strainers having a hook and a pull connection comprising a part connected to the hook at the outer end of the latter and extending over and across the middle 40 portion of the hook.

14. A strainer connection for coffee strainers having at the lower part thereof an elongated depending member terminating in a hook, the material of said hook being continued integrally 45 as a hook extension from the outer end of the hook in a downward direction and then laterally and upwardly over and across the middle part of the hook and then downwardly and laterally, the last mentioned lateral portion of the hook extension being formed into an eye in substantial alignment with the depending member carrying said hook, and a pull member connected to said eye. 50
